UNITED STATES PATENT OFFICE.

CHARLES E. DE LONG, OF SPRINGFIELD, ILLINOIS.

TRUING JEWEL SETTINGS.

Application filed September 12, 1921. Serial No. 499,920.

To all whom it may concern:

Be it known that I, CHARLES E. DE LONG, a citizen of the United States, residing at Springfield, in the county of Sangamon and 5 State of Illinois, have invented a new and useful Appliance for Truing Jewel Settings, of which the following is a specification.

The invention relates to instruments for 10 truing the jewel-settings of watches or other instruments requiring great precision in construction.

The purposes of the invention are: to provide simple and effective means whereby 15 practically perfect coincidence of the axis of the hole in the jewel with the axis of its setting may be attained; to provide a jewel-setting truing-device adapted for use in conjunction with usual watch-makers' 20 lathes, capable of rapid and accurate operation and obviating the difficult and unsatisfactory shellac process hitherto commonly used in jewel setting; to provide a barrel normally in line with and supported by the 25 tail-stock and equipped with a slideable spring-actuated plunger having pivots in line with the axis of the rotative split chuck holding the jewel-setting; to provide a yoke and appurtenances connecting the barrel 30 with the tail-stock spindle in a manner admitting of slight oscillative movement of the end of the barrel relatively to the common axis of the tail-stock spindle and the split-chuck; to provide in conjunction with the 35 barrel a tool holder radially adjustable relatively to the barrel; and to provide other improved structural details.

The invention is illustrated in the accompanying drawing and will now be described 40 in detail and the novel features thereof will be recited in the claims.

Figure 1 is a side elevation of a jewel-setting truing-appliance embodying my invention, shown in operative relation to a 45 watch-maker's lathe;

Fig. 2 is a greatly enlarged longitudinal axial section through the same jewel-setting truing-appliance; and

Fig. 3 is an enlarged perspective view of 50 the detached plunger.

The same reference numerals designate the same parts in all the views.

The lathe bed 5, the head-stock 6, the split-

chuck 7, the tail-stock 8 and the tail-stock 55 spindle 9 are of usual construction.

The steel barrel 10 is preferably of the external form shown in Fig. 1 and has a longitudinal smooth bore 12 extending the greater part of the length of the barrel and a relatively short reduced internally screw-threaded bore 13 receiving a screw 14 coaxial with the barrel.

A bushing 15 is fitted in the bore 12 and is secured by a screw 18.

The plunger 3 slides in the longitudinal bore of the bushing and has a flat part 3^a and also has at each end a pivot 16 adapted to enter the hole in a jewel 4.

A pin 17 driven in a hole in the wall of the bushing has its inner end near but not 70 touching the flat face 3^a of the plunger. The pin prevents rotation but does not interfere with free sliding of the plunger in the bushing. In case one of the pivots 16 becomes worn or damaged the plunger may 75 be reversed and the other pivot may be used.

A follower 19 sliding freely in the bore 12 has a central hole 20 receiving the pivot 16 of the plunger 3 and the follower surrounding the pivot protects it from injury. 80

A coiled spring 21 occupies the bore 12, is compressed by inward movement of the follower upon inward sliding of the plunger and acts to slide the follower outwardly to cause outward sliding of the plunger. 85

The yoke 22 has a tapered shank 23 which engages in a tapered socket 24 in the tail-stock spindle 9 and has a tapered hole 25 through which the screw 14 extends. The form of the hole 25 permits slight oscillative 90 movement of the screw in the hole. A pin 26 fixed in the body of the yoke extends into a slightly larger hole 27 in the body of the barrel. The pin-and-hole connection

permits slight oscillative movement of the barrel, but keeps it from rotating relatively to the yoke. A spring 28 surrounds the screw 14. Slight oscillation of the barrel 10 stresses the spring and the spring normally acts to keep the barrel horizontal, with the pivots 16 of the plunger 3 in line with the axis of the chuck 7, so that when the tail-stock spindle 9 is pushed inwardly the pivot 16 will enter the hole in the jewel 4 mounted in the jewel-setting 29 held in 100 the chuck 7.

105

A spring steel tool-holder 30 is parallel to the barrel and is secured thereon by a screw 31. The tool holder has a longitudinal member 35 which extends into a longitudinal slot 36 in the body of the barrel 10. The member 35 moves in the slot 36 to guide outward radial movement of the tool holder relatively to the longitudinal axis of the barrel, and the member engaging 15 on the side walls of the slot prevents lateral movement of the tool holder. The tool holder has also an inclined way 37 accommodating the cutting tool 33. The tool may be set in different positions in the way 37 and may 20 be secured by the screw 34.

The screw 32 screws into and extends through the tool holder and the end of the screw bears on the barrel. Upon advancing the screw inwardly the tool holder will 25 move outwardly more or less, according to the movement of the screw, and upon retracting the screw, more or less, the tool holder will spring inwardly; and thus the cutting edge of the tool may be accurately 30 adjusted relatively to the circumference of the rotating setting 29 and relatively to the axis of the pivot 16 around which the setting and the jewel fixed therein rotate, resulting in accurate truing of the circumference of the jewel-setting relatively to the 35 centre of the hole in the jewel.

It will now be observed that under these circumstances the pivot 16 and tool holder 30 are both supported on a member which 40 may be properly described as a floating member, so that movement of the pivot 16 will be accompanied by corresponding movement of the tool holder.

The appliance herein set forth is specially designed for use in watch factories. I have found by experiment that where the appliance is used, the cost of truing jewel-settings is reduced nearly fifty per cent below the cost of truing settings by means of 45 the shellac process hitherto commonly used.

A common method of making jewel-settings consists in taking a tube of suitable internal calibre and cutting the tube into tubules, each of suitable length for a jewel-setting; counter-boring the respective tubules to form in each a recess adapted to receive a jewel; and spinning the inside rim of the setting to secure the jewel in the setting. The holes drilled 50 in the plates of a watch to receive the jewel-settings must be accurately located relatively to each other and accurately calibrated to receive the respective jewel-settings.

In practice, it is found very difficult to 55 set the jewel in the setting so that the axis of the hole in the jewel will accurately coincide with the axis of the setting. It is therefore necessary to true the setting with 60 reference to the hole in the jewel so that

when the setting, after being trued, is placed in the proper hole in the plate, the hole of the plate, the setting contained in the hole, and the jewel contained in the setting will all be absolutely concentric.

70

Operation.

When the barrel and appurtenances are assembled as described, the shank 23 will be inserted in the socket 24 of the spindle 75 9. The jewel-setting to be treated will be placed in the chuck 7 and the spindle on the head-stock will be rotated in the usual manner to effect rotation of the jewel-setting. The spindle 9 will then be pushed inwardly 80 by hand to cause the outwardly projected pivot 16 to enter the hole in the jewel mounted in the setting and thereupon the setting and its jewel will rotate around the pivot. The arm 30 having been previously 85 adjusted by means of the screw 32 and the tool 33 having been previously adjusted and secured in the way 37, the point of the tool will be in position to true the circumference of the jewel-setting so that the axis of 90 the jewel-setting will exactly coincide with the axis of the hole in the jewel. The spring 28 acting on the screw 14 will tend to keep the projecting end of the pivot 16 in line with the axis of the head-stock so that when the jewel-setting is in place in the rotating split-chuck no manipulation of the barrel will be necessary to align the point of the pivot 16 with the hole in the jewel. It will be obvious, under these 100 circumstances, that the pivot 16 acts as a center of revolution for the jewel, and its setting so that when the cutting tool traverses the circumference of the setting the latter is 105 made truly concentric to the hole in the jewel.

I do not wish to restrict the claims to the precise details of construction herein shown and described since it is obvious that other and varied means for rotating the jewel-setting and the jewel mounted therein around the longitudinal axis of a yielding pivot may be used and still keep within the scope of the claims.

Having fully described my invention what I claim as new and desire to secure by Letters Patent is:

1. The means for truing a jewel-setting with respect to the hole in the jewel mounted in the setting, comprising means for rotating the setting on its axis; a non-rotative slideable element having a pivot adapted to enter the hole in the jewel; and a cutting tool mounted on said non-rotative element and cutting the circumference of the setting while the setting is rotating around the pivot in the hole of the jewel.

2. In an appliance for truing jewel-settings, a non-rotative barrel having a longitudinal bore, in combination with a yield-

130

ing plunger sliding in the bore of the barrel and having a pivot adapted to enter the hole in a jewel, to permit rotation of the jewel and its setting around said pivot, and a cutter carried by the non-rotative barrel and engageable with the circumference of the jewel setting.

3. In an appliance for truing jewel-settings, a non-rotative barrel having a longitudinal bore, in combination with a reversible yielding plunger slideable in the bore of the barrel and having at each end a pivot adapted to enter the hole in a jewel, to permit the jewel and its setting to rotate around either pivot of said plunger.

4. In an appliance for truing jewel-settings, in combination with a non-rotative barrel having a longitudinal bore; a coiled spring in the bore of the barrel; a follower

20 free to slide in the bore of the barrel and movable outwardly by said spring; and an inwardly sliding plunger engaging said follower to compress said spring.

5. In an appliance for truing jewel-settings, in combination with a non-rotative and slightly oscillative barrel having a longitudinal bore; a yielding plunger having a pivot in line with the axis of the bore of the barrel and adapted to enter the hole 30 in a jewel; and yielding means normally effective to maintain horizontally of the barrel.

6. In an appliance for truing jewel-settings, the combination of a yoke having an

outwardly extended shank; a non-rotative 35 barrel flexibly connected with the yoke and having a longitudinal bore in line with the axis of the shank of the yoke; and a non-rotative yielding plunger co-axial with the bore of the barrel and having an outwardly 40 extended pivot normally in line with the axis of the shank of the yoke.

7. In an appliance for truing jewel-settings, the combination of a non-rotative barrel having a longitudinal bore; a spring- 45 pressed plunger slideable in the bore of the barrel and having terminal pivots adapted to enter the hole in a jewel; a tool-holder capable of radial adjustment relatively to the axis of the barrel; and a cutting tool 50 capable of radial and longitudinal adjustment relatively to the outwardly extended pivot of the plunger.

8. A tool for truing the exterior of jewel-settings concentric to the hole in the jewel 55 and comprising a floating member adapted to be carried by the tail stock of a lathe, a centering device adapted to enter the hole in a jewel and carried by the floating member, and a cutter carried by said floating member and adapted to operate on the circumference of a jewel setting.

Signed at Springfield, Sangamon County, Illinois, this 8th day of September, 1921.

CHARLES E. DE LONG.
